BEVERAGE DISPENSER OR SIMILAR ARTICLE

Frederick F. Gunther, Chicago, Ill., assignor to Helmco, Inc., Chicago, Ill., a corporation of Illinois

Application January 31, 1948, Serial No. 144,201

Term of patent 3½ years

(Cl. D2—3)

To all whom it may concern:

Be it known that I, Frederick F. Gunther, a citizen of the United States, and a resident of the city of Chicago, in the county of Cook and State of Illinois, have invented a new, original, and ornamental Design for a Beverage Dispenser, or Similar Article, of which the following is a specification, reference being had to the accompanying drawing forming a part thereof.

On the drawing:

Figure 1 is a front elevational view of the beverage dispenser, or similar article, showing my new design; and

I claim:

The ornamental design for a beverage dispenser, or similar article, as shown.

FREDERICK F. GUNTHNER.
